UNITED STATES PATENT OFFICE.

JAMES A. MITCHELL, OF DAYTON, OHIO.

DESIGN FOR A WIRE-JOINING TOOL.

SPECIFICATION forming part of Design No. 27,755, dated October 19, 1897.

Application filed August 26, 1897. Serial No. 649,647. Term of patent 7 years.

To all whom it may concern:

Be it known that I, JAMES A. MITCHELL, a citizen of the United States, residing at Dayton, in the county of Montgomery and State of Ohio, have invented and produced a new and original Design for a Wire-Joining Tool, of which the following is a specification, reference being had to the accompanying drawings, forming part thereof.

Figure 1 is a detail view showing my design; Fig. 2, an end view of same, these two views being deemed necessary to fully illustrate my design.

A A' are two forked or notched arms; B, a stem set at the junction of the arms A A'. 15

C is a handle; D, a peculiarly-shaped eye.

What I claim is—

The design for a wire-joining tool having the forked or notched arms A A', the stem B, the handle C, and the eye D, as set forth.

JAMES A. MITCHELL.
